CLAIM

The ornamental design for an autoinjector, as shown and described.

DESCRIPTION

FIG. 1 is a perspective view showing a new design for an autoinjector with needle guard and removable cap, showing the removable cap removed;

FIG. 2 is a front view of the autoinjector of FIG. 1;

FIG. 3 is a rear view of the autoinjector of FIG. 1;

FIG. 4 is a left-side end view of the autoinjector of FIG. 1; FIG. 5 is a left-side end view of the autoinjector of FIG. 1 with the removable cap removed to illustrate an end view of the needle guard;

FIG. 6 is a right-side end view of the autoinjector of FIG. 1; FIG. 7 is a top view of the autoinjector of FIG. 1; and FIG. 8 is a bottom view of the autoinjector of FIG. 1; FIG. 9 is a perspective view showing an alternative new design for an autoinjector with needle guard and removable cap, showing the removable cap removed;

FIG. 10 is a front view of the autoinjector of FIG. 9;

FIG. 11 is a rear view of the autoinjector of FIG. 9;

FIG. 12 is a left-side end view of the autoinjector of FIG. 9; FIG. 13 is a left-side end view of the autoinjector of FIG. 9 with the removable cap removed to illustrate an end view of the needle guard;

FIG. 14 is a right-side end view of the autoinjector of FIG. 9;

FIG. 15 is a top view of the autoinjector of FIG. 9; and,

FIG. 16 is a bottom view of the autoinjector of FIG. 9.

(Continued)

The broken lines show portions of the design that form no part of the claimed design.

1 Claim, 6 Drawing Sheets
